FIG. IX.

FIG. I.

This technical cross-sectional diagram illustrates a complex mechanical assembly, possibly a lock or actuator. The diagram is labeled with various numbers (e.g., 2, 3, 5, 6, 8, 10, 13, 17, 18, 20, 21, 23, 25, 26, 30, 31, 32, 33, 35, 36, 37, 38, 39, 40, 41, 42, 43, 44, 45, 46, 47, 48, 49, 50) and section lines (II, III, IV, V) to identify specific parts and sections. The assembly includes a central vertical column with various plates, pins, and a central cavity. A horizontal rod or handle is shown at the top and bottom. The diagram is oriented vertically, with labels on the left and right sides.

COMBINED BAFFLE AND HEAT CONSERVER
MEANS

George Faulds, Philadelphia, Pa.

Application April 29, 1939, Serial No. 270,756

8 Claims. (Cl. 158—7)

This invention has reference to heating installations including an intermittently fired burner having an associated refractory baffle functional to effect flame diffusion within the combustion chamber while it, more particularly, relates to such installations including a ring burner and annular baffle.

Installations of the kind referred to while satisfactory to a great extent ordinarily direct the flame locally, within the combustion chamber, with the result that a considerable amount of the thermal units are concentrated and enter the flue before expanding their full effect with resultant waste, while the wall of the combustion chamber is subjected to zonal burning and premature deterioration, whereas the general thermo-conductivity is only in part effective.

The primary object of this invention is to obviate the noted undesirable features by provision of an improved refractory and heat conserving means preferably, although not essentially, devised for service in gas fired heaters whereby the flame is efficiently distributed within the combustion chamber confines in a manner more conducive to well distributed usage of all the generated thermal units before they can attain the outlet or flue of said chamber.

Another object is to provide a thoroughly efficient baffle and heat conserver means having a novel type of crown with differentially-disposable series of annularly-overlapping baffles functional to variably "whorl" the flow of heated air and flame about the upper region of the combustion chamber.

With the above recited and subsidiary objects, as well as ancillary advantages, in view this invention consists in the constructive features, combinations and arrangements of parts whereby the contemplated objects are attained, as hereinafter more fully disclosed, typically illustrated by the accompanying sheets of explanatory drawings, and more particularly defined in the concluding claims.

In the drawings:

Fig. I is a broken vertical section through a gas-fired domestic heater embodying one practical form of the present invention.

Fig. II is a horizontal section on the plane designated II—II in the preceding illustration.

Fig. III is a similar section on the plane III—III of Fig. I, but drawn to a larger scale.

Fig. IV is a perspective view showing two interengageable components, includable in the combined baffle and heat conserver means of this invention.

Fig. V is a broken top plan view of the baffle and heat conserver crown as hereinafter more fully described.

Fig. VI is a fragmentary sectional view taken approximately on the plane VI—VI in Fig. V, with two reversely-pitched baffle blades applied thereto, said section being drawn to a larger scale for purposes of clearness.

Fig. VII is a perspective view of an air-choke member, the purpose of which will be hereinafter fully disclosed.

Fig. VIII is a perspective view of a juncture-piece later on clearly explained.

Fig. IX is a fragmentary sectional view of a slightly modified form of the invention.

Fig. X is a horizontal section on the plane X—X in Fig. IX.

Fig. XI is a fragmentary plan view of a different type of crown and blade arrangement usable with either form of the baffle and heat conserver shown in Figs. I and IX.

Fig. XII is a section taken approximately on the plane XII—XII in Fig. XI; and,

Fig. XIII is a perspective view of one of the crown-blades hereinafter fully described.

Referring more in detail to the drawings and firstly to Figs. I—VII inclusive, a conventional form of heater structure is comprehensively designated 1 and preferably comprising a standard type of gas control 2, with a ring burner 3 in the lower part of the combustion chamber 4, and a pilot 5; while the burner 3 includes an annular cupped refractory baffle support 6: all of said parts being in accordance with prevailing practice and merely referred to herein for the purpose of better explaining the present improvements.

In accordance with the instant invention instead of mounting a flaring type of refractory material baffle in the cupped support 6, as heretofore, use is made of an annular cast iron baffle preferably comprising corresponding sectoral units 7 which, when assembled, provide an inverted hollow frusto-conical structure 8. Each unit 7, as best understood from Fig. IV, is of 45 arcual transverse contour with an internal flange 9 at the lower edge for seating in the cupped support 6, and an upper flange or outer rim 10 around the top edge, as well as a rib or tongue 11 along one of the straight edges 12 with a complementary groove 13 in the other straight edge 12, for reception of the tongue 11, of an adjoining unit 7. Thus it will be apparent that when the respective units 7 are assembled to form the structure 8 the respective tongues 11 and 55

grooves 13 will interengage and substantially close the joints formed by the abutting straight edges 12. In addition, each unit 7 is provided intermediate the upper and lower edges with an inner arcual flange 14 which, when said units are assembled, lie in a common horizontal plane, for a purpose later on set forth.

In order to interlock the units 7, in assembly, apertured lugs 15 are provided at one inner side 10 of each unit for coaction with an interengageable corresponding apertured tongue 16 on the other side of an adjoining unit 7, so that when the said units 7 are brought into abutting relation a headed drop-pin 17 may be inserted in the larger diameter registering apertures 18 of said lugs 15 and tongue 16, to hold them against dislodgment in use and from relative separation under expansion and contraction influences. A suitable opening such as 19 may be provided in, 20 or cut-out from, one of the baffle units 7 to accommodate different radial locations of the pilot 5, and associated igniter means not shown, relative to the axis of the ring burner 3, for fitment with an appropriate shield 20, in accordance with known practice, to prevent draft 25 through the baffle structure 8 from blowing-out said pilot when ignited.

Seating on top of the baffle structure 8 with interposition of appropriate spacer-blocks 21 30 grooved to break-joint over the top of the abutting straight edge 12, to interlock said edges against relative movement, as well as affording substantial support for the crown 22, and also to define arcual-openings 23 around the upper 35 edge of the structure 8, for a purpose herein-after explained. The spacer blocks 21 may be of the type shown in Fig. I; or they can be substituted by juncture-pieces of the inverted L-section 24 shown in Figs. VIII-X as later on 40 again referred to.

The crown 22, as best understood from Figs. V and VI preferably comprises complementary concavo-convex halves 25 embodying circumferential flange portions 26 having spaced concentric 45 ribs 27, 28, 29, for instance, with intervening arcual slots 30, and axial aperture-forming central parts 31. In addition, the concavo-convex half portions 25 include an annularly arranged series of spaced holes 32 with communicating 50 radially-directed outwardly-diminishing grooves 33, the function whereof will later on set forth. Or, as shown in Figs. XI and XII the crown 22 may embody a perimetric rib 29, radial slots 34, and annularly-arranged spaced arcual projections 55 or lugs 35, in place of the inner ribs 27, 28, and intervening arcual slots 30 of Figs. V and VI.

In order to check the air draft through the baffle structure 8, a concavo-convex truncate-shaped choke device 36, having an axial opening 36' and a series of flow-distributing apertures 37 therethrough, may be seated on the arcual flange 14; and fitting on the crown central part 31 is an appropriate waterback 38 having inlet and outlet service connections 39, 40, respectively.

Baffle devices or blades 41, 41', are disposed around the crown 22 in edge-overlapping relation to induce rotary turbulence of the heated 70 air and products of combustion in the upper part of the chamber 4; and in order to augment effective distribution, the respective annular series of such blades 41, 41', are preferably relatively reversed. In other words, the outer ring 75 of the baffle blades 41 may all be angularly pitched

to direct the rising heated air and flame upwards under rotary action for example, and the partially-overlapping inner series 41' reversely pitched to deflect said heated air downwards under similar action whereby the aggregate 5 amount of such heated air passing through and above the crown 22 is locally concentrated around the water-back 38 with increased thermal efficiency, while better circulation of hot water throughout the system served by the heater 1 10 is attained as well as quicker heating of the water-back 38, for domestic purposes. In order to vary the arrangement of the series of baffle blades 41, 41'; the former for example are individually provided with a grooved arcual-section 15 foot 42 adapted to fit on the outer crown-rib 29; while it is to be noted the inner ribs 27, 28 being of differential curvature are radially reduced in width or thickness so that the foot section groove 43 will also engage thereon. In 20 practice the arcual curvature or sectoral dimension of the arcual groove 43 is proportioned to fit the rib 29, and also of such dimensions radially and curvilinearly that when applied to the rib 27, the radial end edges thereof will impinge said latter rib, and when engaged on the intermediate rib 28 rest loosely thereon, in an obvious manner. In some instances, and preferably to better differentiate the baffle blades 41, 41', the latter series may be formed with solid 30 foot pieces 44, Figs. VI and XIII having shouldered somewhat rectangular projections 45 arranged to engage in the arcual slots 30, said projections being of appropriate cross-section crosswise or transversely to prevent pivotal 35 movement, when inserted into the slots 30. On the other hand the baffle blades 41' of Figs. XI and XII have their foot pieces 44 provided with rectangular or other shaped apertures 46 for coaction with the lugs 35 to 40 likewise prevent pivotal movement thereof.

Referring now to Figs. VIII-X inclusive it will be observed that the upper portion of the baffle units 7 are provided with "fish-tail" projections 47 that define intervening recesses or 45 openings 48 when the crown 22 is seated thereon; also that use is made of the inverted L-shaped juncture-pieces 24, instead of the spacer blocks 21 hereinbefore referred to.

In operation of the baffle structure 8 of this 50 invention, the annular flame ascending from the burner 3 will heat said structure to a high degree of incandescence whereby the entrained upward flow of combustion supporting air within and without such structure will be rapidly 55 raised in temperature and, by influence of the choke device 36, prevented from too free passage through the crown 22, with the result that the atmosphere in the lower portion of the combustion chamber 4 is thermally intensified and 60 a better circulation of water through the heater jacket 49 and back 38 attained. In addition the thermal effect of the burner flame will be 65 annularly directed around the inner wall 52 of the water jacket 49, from the lower region 66 upwards, until it attains the outer and inner series of arcual slots 30 through which the 70 choked flow will partially pass to the baffle blades 41, 41' for annular reverse "whorling" distribution within the combustion chamber 4 uppermost 70 region, before discharge by way of the flue opening 51. Simultaneous with the action just described the other portion of the heated air and flame will, under the up-draft action within the 75 structure 8, be drawn radially inwards through 75

the arcual openings 23, or 48 below the crown 22, and commingling with the intensely heated air passing out of the choke aperture 36 and flow-distributing apertures 37 become thermally intensified before axial concentration by the radial grooves 33 for passage out of the annular series of holes 32 against the water-back 38.

From the foregoing it will be readily understood that by this invention thermal efficiency of heating installations of the type indicated will be considerably increased, and it is desired to include within the scope of the following claims all reasonable variations in the structural details as the state of the prior art permits.

15 Having thus described my invention, I claim:

1. A combined baffle and heat conserver means comprising a hollow truncate structure of interengaged sectoral units, each said unit embodying a tongue lengthwise of one radial edge, 20 and a complemental groove in the other radial edge, said tongue and groove serving when the units are assembled in edge abutting relation to close the joints thereat, means for detachably securing the units in assembled relation, a crown 25 for the truncate structure having a surrounding flange with projections and intervening apertures, and edge-overlapping baffle blades adapted for coaction with said projections to define reversely-pitched annular flow passages there- 30 through.

2. A combined baffle and heat conserver means comprising a hollow frusto-conical structure of interengaged sectoral units, each said unit embodying a basal flange and an upper peripheral 35 rim with a tongue lengthwise of one straight edge and a complemental groove in the other straight edge, said tongues and grooves serving when the units are assembled in edge abutment to close the joints thereat, means for detachably 40 securing the units together, a crown for the frusto-conical structure having a surrounding flange embodying a peripheral rib and spacially related inner projections with intervening apertures, and edge-overlapping baffle blades having 45 foot pieces adapted for coaction with the rib, projections and slots, to define reversely-pitched annular flow passages through and about the crown aforesaid.

3. A combined baffle and heat conserver means 50 comprising a hollow frusto-conical structure of interengaged sectoral units, each said unit embodying a basal flange and an upper peripheral rim with a tongue lengthwise of one straight edge and a complemental groove in the other 55 straight edge, said tongues and grooves serving when the units are assembled in edge abutment to close the joints thereat, spacer blocks adapted to seat over the top part of the structure joints

defined by the abutting units, spaced apertured lugs and an apertured tongue inwardly of each unit arranged for mutual registration with those of the adjoining units, a freely-fitting drop pin insertable in the apertures of the respectively 5 registering lugs and tongues for detachably securing the structure forming units in assembled relation, a crown for the frusto-conical structure having a surrounding flange embodying peripheral and inwardly spaced concentric projections 10 with intervening apertures, and edge-overlapping baffle blades embodying foot pieces adapted for coaction with the peripheral and concentric projections to define reversely-pitched annular flow passages through and about the crown 15 aforesaid.

4. A combined baffle and heat conserver means as defined in claim 3 wherein each of the frusto-conical structure units is formed with an inwardly directed basal flange and an outward rim 20 at the top, each said unit being further characterized by an inner arcual flange intervening the top and bottom, said flanges being located in a common plane when the frusto-conical structure is assembled, and an inverted disked choke 25 having a central orifice with an annular series of spaced flow-distributing apertures seated on said common plane flanges.

5. A combined baffle and heat conserver means as defined in claim 3 wherein each frusto-conical 30 structure unit is provided around the upper rim portion with spaced fish-tail projections defining intervening arcual recesses, and the spacer blocks are of inverted L-shaped formation.

6. A combined baffle and heat conserver means as defined in claim 3 wherein the crown is made in complemental halves with a surrounding flange embodying a peripheral rim and inner concentrically arranged annularly spaced projections, radial slots intervening said flange and 40 projections, and baffle blades having foot portions with suitable apertures for coaction with the projections to prevent pivotal movement thereof.

7. A combined baffle and heat conserver as 45 defined in claim 3 wherein some of the baffles have foot portions with arcual grooves therein for snug engagement around the crown peripheral rib and the concentric projections are of relatively reduced radial width for reception of 50 correspondingly grooved baffles.

8. A combined baffle and heat conserver as 55 defined in claim 3, characterized by inner baffles having foot pieces with relatively reduced lower end projections for seating in the crown flange apertures.

GEORGE FAULDS.
